UNITED STATES PATENT OFFICE.

CHARLES M. TAYLOR, OF PARIS, KENTUCKY.

PRUNING IMPLEMENT.

1,150,718.

Specification of Letters Patent. Patented Aug. 17, 1915.

Application filed November 19, 1912. Serial No. 732,229.

To all whom it may concern:

Be it known that I, CHARLES M. TAYLOR, a citizen of the United States, residing at Paris, in county of Bourbon and State of Kentucky, have invented certain new and useful Improvements in Pruning Implements, of which the following is a specification.

This invention relates to an improvement 10 in pruning implements, and the object is to provide a head having a cutting blade so mounted thereon that the initial cut of the limb will be above the horizontal diameter of the limb, and by such an arrangement of 15 parts the aid of gravity is obtained in the cutting operation.

The invention consists of certain novel features of construction and combinations of parts, which will be hereinafter described and pointed out in the claims.

In the accompanying drawings:—Figure 1 is a perspective view of the invention; Fig. 2 is a view in elevation showing the blade in a position just after having made 25 its initial cut: and Fig. 3 is a view in elevation similar to Fig. 2 showing the blade in a farther advanced position.

A, represents the head which is provided with a hook 1. The hook is provided with 30 an extension 2, which has an inner circular curvature, which is carried on a line radial to a point opposite the initial cutting operation.

The circular curvature of the extension 2, 35 is indicated from *a* to *b* on the drawing, and it is upon this portion of the hook that the greatest resistance is brought to bear during the cutting operation.

A blade B is pivotally mounted on the head 40 A, at a point above the curvature of the hook 1. The blade is eccentrically mounted on the head so that it produces a shearing cut during its movement across the opening formed by the hook and extension.

45 A guard 3 is connected to the head A for holding the blade against the head to insure a positive cutting action by the blade upon the object held by the hook and extension. The cutting edge 4 of the blade is preferably circular so that a large cutting surface is provided.

50 After the limb or object to be cut is inserted in the opening formed by the hook 1, the blade B is drawn downward upon the limb, forcing the limb into engagement with the extension 2 along the surface *a* to *b*.

This circular curved surface of the extension is sufficiently extended to afford complete resistance to any downward pressure of the blade during its cutting operation 60 upon the limb, and especially is this true during the initial cutting operation. The blade comes in contact with the limb above the horizontal diameter of the limb, and the tendency would be for the limb to be forced 65 from the hook, but by providing the extension with a curved surface, the curved surface will hold the limb and receive the pressure exerted upon the limb by the blade in cutting. The object in having the blade 70 cut from above the horizontal diameter of the object being cut, is to overcome the usual upward pressure exerted on the blade during the cutting operation. With this device the blade is being pulled or drawn down- 75 wardly, and as it is eccentrically pivoted to the head A, it will produce a cross-fiber cut, and a gravity cut is obtained rather than upward pressure cut.

Having fully described the invention, and 80 what is claimed as new and desired to be secured by Letters Patent, is:—

1. A pruning implement comprising a hook having its opening from below, a portion of the curvature of the interior of the 85 hook being more pronounced than the remaining portion for forming a projection to engage a branch during the cutting operation, and a blade pivoted at a point above the inner upper surface of the opening of 90 the hook, said blade having a cutting edge eccentric to the pivot, which cutting edge traverses the upper portion of the inner curvature of the hook, first with an endwise slicing cut at a point upon the limb above 95 the horizontal axis approximately diametrically opposite to the curvature of resistance, so that the cut is facilitated both by the end- 100 wise slicing of the knife and by the weight of the limb.

2. A pruning implement, comprising a hook having the opening from below, and the curvature of the hook being more pronounced at the free end thereof, and a blade eccentrically pivoted to the top of the hook 105 at a point in a line substantially at right angles to the tangent to the pronounced curvature of the hook, so that the initial cut into the limb is at a point above the horizontal diameter of the limb, and the free 110 end of the hook with the pronounced curvature having a portion thereof extending in-

wardly for receiving the limb and resisting any downward pressure exerted by the blade during the cutting operation.

3. A pruning implement, comprising a hook having the opening from below, and the curvature of the hook being more pronounced at the free end thereof, and a pivoted blade having a curved cutting edge eccentric to the pivot of the blade for producing a sliding cut, said blade being pivoted to the top of the hook above the opening of the hook at a point in a line substantially at right angles to the tangent to the pronounced curvature of the hook, so that

the initial cut into the limb is at a point 15 above the horizontal diameter of the limb, and the free end of the hook with the pronounced curvature having a portion thereof extending inwardly for receiving the limb and resisting any downward pressure exerted by the blade during the cutting operation. 20

In testimony whereof I affix my signature, in the presence of two witnesses.

CHARLES M. TAYLOR.
